UNITED STATES PATENT OFFICE.

CHARLES F. MOORE, OF GILLETT, PENNSYLVANIA.

AUTOMATIC BRAKE.

SPECIFICATION forming part of Letters Patent No. 363,251, dated May 17, 1887.

Application filed January 8, 1887. Serial No. 223,785. (No model.)

To all whom it may concern:

Be it known that I, CHARLES F. MOORE, of 5
Gillett, in the county of Bradford and State
of Pennsylvania, have invented a new and
Improved Automatic Vehicle-Brake, of which
the following is a specification.

This brake belongs to that class of vehicle- 10
brakes in which the brake is automatically
applied to the rear wheels by the holding back
of the horses in descending a hill or in stop-
ping, and in which the brakes are also discon- 15
nected automatically when it is desired to back
the vehicle; and, more particularly, this inven-
tion belongs to that class of automatic brakes
which are used with vehicles having a pole 20
which supports a sliding rod, the rod being
connected to the yoke or holdback straps at
its forward end and to the brake-operating
mechanism at its rear end.

25 The invention is illustrated in the accom-
panying drawings, in which—

Figure 1 is a plan view of the running-gear
of a vehicle provided with the brakes. Fig.
2 is a side elevation, partly in section; and
25 Figs. 3, 4, 5, and 6 are views of parts in detail.

30 A A are the front wheels; B, the front axle;
C C, the rear wheels; D, the rear axle; E, the
reach, fixed to the rear axle and pivotally con-
nected to the front axle at a; and F, the pole,
pivotally connected by bolt b to the hound- 35
frame G.

H is the sliding rod, which is carried on top
of the pole F. This rod has on its front end
a cap, I, which fits over and slides upon the
35 end of the pole, and on its rear end a plate,
J, having longitudinal slots c c, which embrace
headed guide-bolts d d, secured to the pole,
which hold the plate J in position on the pole
and permit a limited sliding movement there- 40

40 To the rear end of the pole-plate J is hinged
a short bar, e, between which and the pole-
plate is pivoted the whiffletree f, which slides
back and forth with the sliding rod.

45 The cap I of the sliding rod is adapted to
be connected with the yoke or holdback straps
of the harness, it being shown with a depend-
ing lip, g, for that purpose. When the horses
hold back, the cap I will be moved backward, 50
and with it the sliding rod and whiffletree, and

when the horses again pull forward on the
whiffletree the sliding rod and cap will be
moved forward. This backward movement
of the sliding rod is utilized to apply the
brakes, and the forward movement releases 55
them.

The brakes employed may be of any usual
or desired kind. In the drawings a brake-bar,
K, is shown extending beneath the reach in
front of the rear wheels. This bar is pivotally 60
suspended by links h h from a cross-arm, i,
secured to the reach. On the outer ends of the
brake-bar are carried the brake-blocks L L—
one for each wheel. The rearward movement
of the brake-bar applies the brakes, and its 65
forward movement releases the same. The
connection between the brake-bar and the slid-
ing rod H is as follows: Rigidly secured to the
pole-plate J are two downwardly and out-
wardly projecting arms, M M, which embrace 70
the pole F on either side. These arms are
pivoted by bolt m to a coupling, N. To this
coupling is pivoted at n a rod, o, extending be-
neath the reach and parallel therewith. The
pivotal connection between the extensions M 75
M, the rod O, and coupling N, which turn in
planes at right angles to each other, constitut-
ing a universal joint, permit the brake to be
always applied without interfering with the
rise and fall of the pole or the turning of the 80
front wheels.

Hinged at o to a plate, Q, on the top of the
reach, near the rear axle, is a yoke lever or strap,
R, embracing the reach and extending below
the same. The lower end of this yoke-lever 85
is pivoted at y to an ear, s, on a tubular sleeve,
S, which embraces and is keyed to the rod O
by a key, t. By this means the sleeve S can
be secured to any part of the rod O, so that
the same mechanism can be applied to any 90
size of vehicle. The key has projections u u
at each end, so that if accidentally loosened
when in use it cannot become lost, the rod O
projecting far enough behind the sleeve so that
it cannot be disconnected therefrom when the 95
parts are once secured to the vehicle.

Between the pivots o and y of the yoke-le-
ver, one pivoted on either side thereof, at v, are
rods T T, which at their other ends are rigidly
connected to the brake-bar K. It will be seen 100

that backward movement of the sliding rod H moves backward the extensions M M, the rod O, the yoke-lever R, and the brake-bar K, thus applying the brakes, and that a forward 5 movement of the whiffletree disengages the brakes.

In order that the brakes need not be applied when it is desired to back the vehicle, the 10 brake-blocks L L are hinged to the upper side of the bar K by hinges W. When the wheels are moving forward, the brakes will act upon them; but when the wheels are moving backward their friction on the brake-blocks will swing the latter upward on their hinges, thus 15 disengaging them.

I claim as my invention—

1. The turning front wheels of a vehicle, the pole pivotally connected thereto, a sliding brake-operating rod carried by said pole, and 20 brakes which co-operate with the rear wheels of the vehicle, in combination with downward extensions M M, rigidly secured to the said sliding rod, longitudinal rod O, extending beneath the vehicle and connected with the brake 25 mechanism, and coupling N, pivoted to said extensions M M and rod O, the pivots being such that the planes in which they turn are at right angles to each other, substantially as set forth.

30 2. The pole of a vehicle, a sliding brake-operating rod carried thereby, said rod having

a cap which fits over and slides upon the end of the pole, and having also a slotted plate, by which it is connected to the pole so as to slide thereon, and the whiffletree carried by and 35 sliding with said sliding plate, in combination with the swinging brake-bar K, brake-blocks L L, carried by said brake-bar, downward extensions M M, rigidly secured to the said sliding rod on the pole, longitudinal rod O, connected to said extensions and extending beneath the body of the vehicle, the yoke-lever R, pivoted at opposite ends to the reach and to said longitudinal rod O; and the rods T T, attached at opposite ends to the brake-bar K 40 45 and to the yoke-lever between the pivoted points thereof, substantially as herein set forth.

3. The yoke-lever R and the longitudinal rod O, in combination with the coupling-sleeve S, connected to the yoke-lever, and through 50 which the rod O passes, and the key t, having projections u u at each end, said key connecting said sleeve and rod, substantially as herein set forth.

In witness whereof I have hereunto signed 55 my name in the presence of two subscribing witnesses.

CHARLES F. MOORE.
